UNITED STATES PATENT OFFICE

157,327

TELEVISION RECEIVER

E. Burton Benjamin, New York, N. Y.

Application November 22, 1948, Serial No. 149,745

Term of patent 3½ years

(Cl. D56—4)

To all whom it may concern:

Be it known that I, E. Burton Benjamin, a citizen of the United States of America, residing at 390 Riverside Drive, New York city, county and State of New York, have invented a new, original, and ornamental Design for a Television Receiver, of which the following is a specification, reference being had to the accompanying drawing, forming part thereof in which the opposite side of the design is similar to the one illustrated in the drawing, and the figure is a side perspective view of a television receiver, showing my new design.

I claim:

The ornamental design for a television receiver, as shown and described.

E. BURTON BENJAMIN.
